UNITED STATES PATENT OFFICE.

WILLIAM PATTERSON, OF SAN FRANCISCO, CALIFORNIA.

STEAM AIR-SHIP.

SPECIFICATION forming part of Letters Patent No. 340,610, dated April 27, 1886.

Application filed June 20, 1885. Serial No. 169,316. (No model.)

To all whom it may concern:

Be it known that I, WILLIAM PATTERSON, a resident of the city and county of San Francisco, State of California, have invented a 5 novel and useful Steam Air-Ship; and I hereby declare that the following is a full, clear, and exact description of the same, reference being had to the accompanying drawings.

My invention relates to means for navigating the air with facility by combining a balloon attached closely to a car with steam-motors placed in the car, the form and construction of the car and the manner of attaching the balloon thereto producing rigidity and 15 stability in the structure, in which the driving instrument is placed in the stern and acts both as propeller and rudder.

The following description fully explains the nature of my said invention and the manner in 20 which I proceed to construct, apply, and operate the same, the accompanying drawings being referred to by figures and letters.

Figure 1 is a general elevation view of the steam air-ship. Fig. 2 is an elevation view 25 of the balloon, showing the compartments, valve-openings, and throats, and showing in dotted lines the gas-tight closets and pipes, which lead to the exterior of the balloon. Fig. 3 is an end view of the balloon, showing 30 the valve-opening, the throat, and the large and small aprons. Fig. 4 is a stern view of the balloon and car, showing the mouth of the stack and the iron bands on the car and their adjustment. Fig. 5 is an enlarged view of the 35 stern propeller and crane-frame. Fig. 6 is a plan view of the same. Fig. 7 is an end view of the same. Fig. 8 is an enlarged view of the bumper-wheel and its arrangement. Fig. 9 is an elevation view of the same. Fig. 10 represents a section of the same. Fig. 11 is an 40 elevation view of the same. Fig. 12 is an elevation view of the balloon-netting and attaching-straps. Fig. 13 is an enlarged elevation view of the automatic whistle and valves. Fig. 14 is an end view of the same. Fig. 15 is a plan view of the same. Fig. 16 is a plan 45 view of the valves. Fig. 17 represents a section through the car, showing the parachute-arms. Fig. 18 is a detail view of the 50 parachute-shaft. Fig. 19 represents a section through the car, showing the arrangement for

setting and furling the parachute. Fig. 20 is a plan view of the same. Fig. 21 is a detail view of the arrangement for attaching the balloon and the netting to the car. Fig. 22 55 is a longitudinal sectional view of the ship, showing the boiler, water-tanks, and connections. Fig. 23 is a sectional view of the pipes F and F* at their juncture, showing the dampers in them. 60

In the construction of my steam air-ship my object is to combine lightness and strength in a form to offer the least resistance. I build the car in the form of a cylinder pointed at both ends and having a flat deck and the central part of the bottom flat. The frame is built of ash or other suitable wood, and consists of a series of ribs placed at required distances attached to keelsons. The frame is planked or closed in for one-half of its depth, 65 or any required depth, with three-ply birch veneering or other suitable material, above which a wale extends around the car. The intervening space between the planking and the deck is closed with rope-netting or other 70 suitable material, Figs. 1, 4. The ribs are attached to the deck-timbers below the gunwale, the deck-timbers projecting over the hull of the car. The overhanging deck, which is laid of suitable wood, is provided with a rail covered with rope-netting, which extends around the deck. The flat space in the bottom of the car is floored, on which is placed timbers or beds for the engines and boilers. There are two or more doors conforming to the shape 75 of the car on each side. The car is braced diagonally athwart, and is trussed diagonally fore and aft by rods adjusted by turn-buckles. The stern of the car is left open for the operation of the stern propeller-shaft and braces, 80 Figs. 1, 4. The car is braced and protected by flat bands of iron, s, which pass transversely across the bottom of the car and thence at an angle to the overhanging deck-beams, and at the required distance from the end of 85 the beams the iron band forms a square collar, which fits over the beam. On the upper side of the collar there is an eye, which projects through the deck, to which is attached a sister hook, T, for securing the balloon, and a 90 stirrup, U, for securing the netting, Fig. 21. Between the deck and the edge of the bottom 95

of the car each iron band is provided with a turn-buckle, R, for the purpose of adjusting it, Fig. 4.

The car is mounted upon four or more bumper-wheels, G, placed equidistant on each side. The wheel is formed by a cast-iron hub having wrought-iron flat or round spokes and a wrought-iron felly, the spokes being set in the hub, as shown, Fig. 10. The axle works in the yoke of the shaft, m, which passes through a collar, n^x, and a bush, z^x, into and through the journal-box o, which is bolted to the side of the car. A spiral spring, l, placed between the collar n^x and the bush z^x, surrounds the shaft, Figs. 8, 9.

At the forward end of the car a stack, F, having a trumpet-shaped mouth, projects a certain distance. The stack is placed horizontally below the deck over the boiler z, to which it is connected by a pipe, F*, and passes to a point near the stern, where it takes an oblique angle and passes out at the stern and terminates in a flaring mouth-piece, which turns on a swivel-joint, Fig. 1.

Two auxiliary propellers, E, attached to shafts, pass through the bottom of the car at points equidistant from the center and between each pair of bumper-wheels, and are operated by one or more engines, y, which are connected directly to the cranks on the propeller-shafts.

At the required distance from the stern of the car is located what I call a "crane-frame," J, consisting of two or more timbers, to the ends of which are bolted iron steps J^x. Each step has a pivot, v, which enters and works in box v^x, the upper box being bolted in the deck-timber and the lower box to the bottom of the car. A journal-box, x^x, in which the stern propeller-shaft, K, has its bearing, is placed on the upper part of the crane-frame, and is bolted to the timbers on both sides. On the lower step of the crane-frame there is bolted a vertical engine, w, the rod of which connects with the crank x on the inner end of the stern propeller-shaft. Bolted to the sides of the lower stem are two or more braces, j, which extend at an angle to the propeller-shaft, where they form or are attached to a collar, h^x, in which the propeller-shaft fits and rotates. Attached to the collar also are tiller-arms k, having eyes at their ends for ropes, Figs. 5, 6, 7.

All the engines are supplied with steam by a boiler, z, placed directly in the center of the car. On the bottom of the car, fore and aft of the boiler, there is a tank or tanks, Z, for a supply of water for the boiler. Exhaust-steam from the boiler is conducted to the water-tanks by flexible pipes, and from the tanks it is conducted by a flexible pipe to the stack F, as shown in Fig. 22.

The balloon A, which I make conform at its bottom to the shape of the deck of the car, is made of cotton cloth or other suitable material. It is divided into three compartments by diaphragms a, composed of the same ma-

terial as the bag, the edges of which are sewed to the seams of the bag. Each compartment is provided with a throat, b, placed centrally in the bottom of the bag, and each throat passes through an opening in the deck of the car into a gas-tight closet having a central position and connected with an escape-pipe, b^x, which passes out of the side of the car and thence at a right angle through the deck of the car between the rail and the balloon, the mouth of the pipe extending above the rail. On the middle upper surface of each compartment there is an opening, c, for a valve-seat, d. The valve-seat is of the ordinary form used in balloons, except that each disk has a cross-bar which is bored in the center for an automatic whistle, H. On each edge of the under side of the cross-bar are hinges for attaching the valve i, which open downward right and left, and in closing overlap both cross-bar and disk. When the valves are closed, they are held in position by a spiral spring, f, the lower end of which is attached to a staple, i^x, in the valve and the upper end to a ring-bolt, f^x, on a leg of the iron frame E, opposite to each other, the legs of the iron frame being bolted to the valve-seats, Figs. 13, 14, 15. The edges of the balloon are re-enforced by a seam formed of one or more plies of the material of which it is made, and eyelets are worked in the seam for securing the balloon to the car, Fig. 2. The balloon is re-enforced on top by an apron, g, which is sewed to it, and around each opening for the valve-seat a small apron, h, is sewed over apron g, Figs. 1, 3.

The netting B, which covers the balloon, consists of flat woven bands of silk or other suitable material, formed in meshes of any required size and angle. At the point of intersection the bands are secured by sewing or cementing or other mode of attachment. The netting has its edge bound to a rope, N, or a rod of wood or metal from which straps of leather or canvas are suspended, each strap having a number of eyelets at regular distances and a metal hook riveted to its end. The end of the strap is passed through the stirrup U on the collar V on the deck-beam, and thence upward to an eyelet in the strap, by which means the netting is fastened to the car independent of the attachment of the balloon. On the top of the balloon the netting has openings, the edges of which are bound for the valve-seats, which the edges overlap and are secured to.

The parachute I is made of canvas or other suitable material, and of any required size. The edges are re-enforced and provided with eyelets. On the upper surface of the canvas metal rings are attached, by which the parachute is suspended from the arms u. The arms are round and are made of wood or metal, and their outer ends are attached to the eyelets in the edges of the parachute. The inner edge of the parachute is attached to the under edge of the deck of the car. In the under side of the required number of deck-beams

two or more collar-bolts, W, Fig. 20, are placed in each beam. The bolt passes through the beam, the lower end or collar receiving and holding the arms *u* of the parachute. On the 5 inner end of each arm there is a hole in which a rope is secured, and thence passes to pulley *r* on the shaft *q*, suspended from the under side of the deck and extending the length of the car, and thence to block *s* on the inner 10 side of the car and on a level with the shaft, Figs. 17, 18, 19, 20. When the parachute is extended it is stayed by a number of guys made of wire or rope, one end of which is attached to a ring on the parachute-arm and 15 the other end to a ring-bolt on the lower edge of the outside of the car, Fig. 19. The guys hang loose on the outside of the car when the parachute is folded. The one edge of the 20 parachute I is attached to the outer ends of the arms *u*, and the other edge to the side of the car, while its mid-width is supported by rings set loosely over the arms *u* and capable of sliding thereon. The arms *u* are drawn inward through the medium of the rope or chain 25 *q*, which is attached to their inner ends, and after passing over pulleys *s* on the sides of the vessel is secured to parts *r* on shaft *q*, as above described, so that by turning shaft *q* in one direction the arms *u* will be drawn inward, 30 and the parachute fold up loosely at the side of the car, and by turning the shaft in the opposite direction the arms will be extended and the canvas of the parachute stretched. The shaft *q* may be operated by hand or may 35 be connected with one of the engines, as may be desired.

In the construction of my balloon I have divided it into compartments by diaphragms *a*, for the purpose of confining a given amount 40 of the gas to each compartment, thus maintaining equilibrium by preventing a rush of gas in volume to one end or the other in case of a sudden pitch of the balloon. Either of the end compartments may burst and collapse, 45 and the gas from the remaining one is allowed to escape through its valve, and equilibrium is maintained by the middle compartment. If the middle compartment bursts, equilibrium is maintained by the end compartment, and 50 if one of the end compartments also bursts, the parachute I is set to the wind by extending the arms *u*, and the auxiliary propellers E are operated by engines *y*, which combined action arrests the descent of the air-ship and 55 causes an ascending movement.

In case it should be necessary to expend a part of the volume of gas, the valves *i* are opened, their operation being similar to those in the ordinary balloon. Each valve is provided with an automatic whistle, H, adjusted to a certain pressure, which, when reached, causes the whistle to sound an alarm and blow off the gas, and thus prevents the danger of over-expansion.

65 The substitution of flat bands for cords in the netting B reduces the resistance, and also lessens the friction by their broad even sur-

face. The common cord - netting is full of knots, which press into the material of the balloon and chafe and wear it. The manner 70 in which I attach the netting to the car is both quicker and safer than the common methods, as the friction of the attaching straps is reduced to a minimum.

The shape which I have adopted for the balloon, which conforms to the deck of the car—that is to say, it has a flat bottom—is straight 75 on top in the center for about one-third of its length, and thence tapers to each end, Figs. 1, 2, offering less resistance to the surrounding 80 medium and opposing current than is presented by other balloons.

The escape-pipe *b*, which passes from each throat *b* of the balloon into the gas-tight closet in which the throat is combined and thence 85 outward through the side of the car, as described, is for the purpose of conducting gas which has escaped by the action of counter-current or excessive expansion and forced itself into the throat.

The horizontal stack F receives at the bow 90 end of the car a supply of air for the furnaces, and is provided with a damper at the intersection of the connecting-pipe F* to the boiler, and a damper is also placed in the intersecting 95 pipe. By the action of the damper in the stack the supply of air is increased or decreased to meet the demands of the furnaces, and by the action of the damper in the intersecting pipe the draft may be shut off from the furnaces 100 without preventing the escape of exhaust steam through the stack.

I have placed the propelling-instrument D preferably in the stern of the car, in order to overcome the tendency to vertical deviation. 105 The propeller acts both to propel and steer the air-ship. It is attached to what I call a "crane-frame," J, holding a vertical engine, *w*, as described, and is worked as a rudder by the tiller-arms *l*, connected by tiller-ropes to the pilot-wheel in the forward part 110 of the car. Acting as a propeller, it is operated by the shaft K, on which it is set by the vertical engine *w*. The position of the propeller at the stern of the extreme points of 115 both car and balloon gives great control in directing the course of the air-ship by exerting a direct propulsive force on the balloon; and acting as a rudder, the propeller prevents the 120 gyroscopic motion experienced by aeronauts in recent experiments.

The auxiliary propellers E, which I have placed in the bottom of the car between each pair of bumper-wheels, Fig. 1, are used for the purpose of assisting the ascent of the balloon 125 and to obviate the necessity for carrying ballast, and by a reverse action induce the descent of the ship without the expenditure of gas. In case of a general collapse of the balloon, they promote, in connection with the action 130 of the parachute, a safe descent of the air-ship.

I have attached the parachute I for the purpose of checking and retarding the descent of the ship in case of a burst or collapse of the

balloon. The parachute is operated by ropes *t*, one end of each of which is attached to the inner end of the arm *u* and thence passes over pulley *r* on the shaft *q* to and through the block *s*, and thence returns to the inner end of the arm *u*, where it is also attached. The ropes attached to the parachute-arms *u* on one side of the car pass over the upper side of the pulley *r* and thence to the block *s* and then return to the inner end of the arms, and on the opposite side of the car the action of the ropes is similar, except that they pass on the under side of the pulleys and then return to the arms. The first operation spreads the 15 parachute beyond the deck of the car, and the second draws it in and furls it in its place on the car.

The object of my bumper-wheels *G* is to react against concussion in landing the air-ship 20 and to facilitate its movements after a landing has been effected. The bumper-action is produced by the spiral spring *l*, acting between the collar *n*^x and the bush *z*^x, which, when the ground is struck, forces the shaft *n* upward 25 through the box *o*. The shaft is round, which permits the bumper-wheel to turn in any direction, Figs. 8, 9.

I claim that my application of an automatic whistle, *H*, as a means of preventing or lessening the danger of collapses in balloons or 30 aerostats of any description is both new and useful. I place the whistle in the valve-seats *d* for the purpose of relieving the balloon from excessive expansion of gas. This is accomplished by adjusting the spring in the whistle 35 to a given pressure, and the instant this pressure is exceeded the whistle sounds the alarm and blows off the gas and the valves are opened, if it is necessary.

40 My steam air-ship is designed for navigating the air with facility without reference to the course of the wind or the altitude. The combination of the balloon with light steam-motors in lifting and propelling the ship gives large 45 control and direction of the course. The form adapted for the ship—a cylinder tapering at both ends and having a nearly straight body in the center where the bottom is flattened, combined with the manner of attaching the 50 balloon and the netting—gives rigidity and stability to the structure; and the auxiliary propellers, combined with the action of the parachute, contributes a large element of safety to my air-ship.

55 Having thus fully described my invention, what I claim, and desire to secure by Letters Patent, is—

1. In an air-ship, the combination of a car, of the form and construction substantially as shown and described, having a flat top, and 60 a balloon secured immediately thereupon having a flat bottom and rounded top, and having throats or tubes leading into the car, and gas-tight closets over the exits or mouths of said tubes in the body of the car, as set forth.

2. In an air-ship, the combination, with the balloon and car, of the throats *b* upon the balloon, the gas-tight closets into which they lead, and the escape-pipes *b*^x, leading from the said closets to the exterior of the structure.

3. In an air-ship, the combination, with the car, of the extensible arms *u*, canvas or parachute secured thereupon in the manner set forth, and means, substantially as described, for extending and withdrawing said arms.

4. The combination of the extensible arms and parachute of flexible material secured thereon with the chains or cords *q*', pulleys *s*, secured on or near the side of the car, over which the chains or cords *q*' pass, and the center shaft, *g*, having the chains or cords secured to it, substantially as and for the purpose set forth.

5. In an air-ship, the combination, with the crane-frame secured in the car of the ship with 85 liberty to swivel thereon, of the propeller secured on a shaft connected with said crane-frame, and the engine *w*, secured in said crane-frame and having its piston-rod connected with the propeller-shaft, as set forth.

6. In an air-ship, the combination, with 90 guide or keeper *o*, inside the car of the ship, of the wheel *G*, having the form *m*, with collar *n*^x, and stem *n*, extending up into the ship and into the part *o*, and the spring *l*, placed round 95 the stem *n*, between the collar *n*^x and the bottom of the car, substantially as set forth.

7. The combination, with the crane-frame *J*, swiveled in the car, the engine secured in said frame, the propeller having shaft extended 100 out from said frame, and a pipe covering said shaft, and the braces *j*, connected at the inner end to the crane-frame and at the outer end to the collar *h*, and the tiller-arms *k*, adapted to receive connections for swinging 105 the frame and its appended parts.

In testimony whereof I have hereunto set my hand and seal.

WILLIAM PATTERSON. [L. S.]
